(57) **CLAIM**

The ornamental design for a single element misting nozzle, as shown and described.

DESCRIPTION

FIG. 1 is a top perspective view of the design of my single element misting nozzle.

FIG. 2 is a front elevational view thereof, in which back, left, and right elevational views are mirror images thereof.

FIG. 3 is a bottom axial plan view of the inventive design.

FIG. 4 is a top axial plan view thereof; and,

FIG. 5 is a view, similar to that of FIG. 2, however showing the position of the single element misting nozzle when positioned relative to a ceiling surface and water conduit which are shown in phantom forming no part of the claimed design.

1 Claim, 5 Drawing Sheets

FIG. 1

FIG. 2

FIG. 3

FIG. 4

FIG. 5
